UNITED STATES PATENT OFFICE.

CHARLES H. VON HOHENSTEIN, OF SAN ANTONIO, TEXAS.

LIQUID-HYDROCARBON BURNER.

1,111,509.

Specification of Letters Patent. Patented Sept. 22, 1914.

Application filed December 22, 1913. Serial No. 308,254.

To all whom it may concern:

Be it known that I, CHARLES H. VON HOHENSTEIN, a citizen of the United States, residing at San Antonio, in the county of 5 Bexar and State of Texas, have invented a new and useful Liquid-Hydrocarbon Burner, of which the following is a specification.

The present invention relates to improvements in a liquid hydrocarbon burner, one 10 object of the invention being the provision by means of which liquid hydrocarbons such as kerosene, crude oil or the like are properly vaporized or gasified so that the same may be readily used in cooking and heating 15 stoves and for generating heat, the liquid being properly vaporized or gasified before the delivery thereof through the burner jet or jets.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

In the drawings—Figure 1 is a diagrammatic perspective view showing the present 30 burner in operable relation. Fig. 2 is a top plan view of the burner *per se*. Fig. 3 is a section taken on line 3—3 of Fig. 1. Fig. 4 is an end elevation of the burner.

Referring to the drawings, the numeral 1 35 designates the liquid hydrocarbon supply pipe which is controlled by the hand needle valve 2 having led therefrom, the horizontal pipe 3 which is secured or projected through 40 the wall 4 of a stove. The opposite end of the pipe 3 is connected to the central inlet of the horizontally disposed T-coupling 5 which has connected to one branch, the L-coupling 6. The union 7 is connected to the 45 other outlet of the L-coupling 6 and is connected to the terminal 8 of the horizontal pipe 9. This pipe 9 is bent to form the legs or parallel members 10, 11 and 12 so that a coil of pipe is properly presented and 50 maintained in a substantially horizontal plane with the outlet of the union 7. The portion 13 of the pipe is bent downwardly in a vertical line, and horizontally to parallel the pipe 8, the terminal 14 being disposed 55 at right angles to the same and extending centrally and below the coil composed of

the bends 9, 10, 11 and 12. The pipe 14, as clearly shown is disposed vertically below and parallel with the fluid introduction pipe 3 and is provided with a slightly inclined upturned end or gas chamber 16 which is 60 plugged as at 17, and provided with a pet cock 18', by means of which the chamber may be cleaned. A burning jet 18 is formed in the jet pipe 15 at a point directly below 65 the center of the disk deflector 20 which is connected by the securing means 19 to the pipe 3. A support 13' is connected to the coupling 5 and embraces the portion 13 and thus assists in properly supporting the 70 coil.

It will thus be seen that with this structure, the burner may be properly disposed within the fire box of any form of stove to properly generate the gas from the liquid hydrocarbon, the coiled portion of the burner being disposed in a horizontal plane so as to be heated from the deflected flames that are issuing from the jet 18 and engaging the under side of the disk deflector 20. Thus the 75 liquid hydrocarbon is properly vaporized and heated and the gas formed thereby will be forced through the jet 18 where the same is ignited to produce the desired heat. Any means for priming or starting the gasifying 80 may be provided.

What is claimed is:

1. A fluid hydrocarbon burner, including a fluid conveying pipe, a T-coupling connected thereto, an L-coupling connected to 90 one outlet of the T-coupling and with its other outlet disposed to project at right angles to the fluid conveying pipe, a horizontally disposed coil connected to the outlet of the L-coupling and disposed below and parallel to the fluid conveying pipe, the terminal of the coil being disposed in a plane below the coil and in vertical alinement with the fluid conducting pipe, said terminal being provided with a gas jet extending toward the fluid conveying pipe, the extreme 95 end of the jet carrying terminal being bent upwardly and terminating at a point in substantially the same horizontal plane as the coil.

2. A fluid hydrocarbon burner, including a fluid conveying pipe, a T-coupling connected thereto, an L-coupling connected to one outlet of the T-coupling with its other outlet disposed to project at right angles to the fluid conveying pipe, a horizontally disposed coil connected to the outlet of the L- 100

105

110

coupling and disposed below and parallel to the fluid conveying pipe, the terminal of the coil being disposed in a plane below the coil and in the same vertical plane as the fluid conveying pipe, said terminal being provided with a gas jet extending toward the fluid conveying pipe, the extreme end of the jet carrying terminal being bent upwardly and terminating at a point in substantially the same horizontal plane as the coil, and means for supporting the coil from the opposite outlet of the T-coupling.

3. A fluid hydrocarbon burner, including a fluid conveying pipe, a T-coupling connected thereto, an L-coupling connected to one outlet of the T-coupling and with its other outlet disposed to project at right angles to the fluid conveying pipe, a horizontally disposed coil connected to the outlet of the L-coupling and disposed below and par-

allel to the fluid conveying pipe, the terminal of the coil being disposed in a plane below the coil and in the same vertical plane as the fluid conveying pipe, said terminal being provided with a gas jet extending toward the fluid conducting pipe, the extreme end of the jet carrying terminal being bent upwardly and terminating at a point in substantially the same horizontal plane as the coil, and a flame deflector mounted upon the fluid conveying pipe directly above the gas jet.

In testimony that I claim the foregoing as my own, I have hereto affixed my signature in the presence of two witnesses.

CHARLES H. VON HOHENSTEIN.
